UNITED STATES PATENT OFFICE

ABRAHAM DEWEY STONER, OF NEW WINDSOR, MARYLAND

DESIGN FOR A RABBIT HUTCH

Application filed September 18, 1931. Serial No. 41,137. Term of patent 7 years.

To all whom it may concern:

Be it known that I, ABRAHAM DEWEY STONER, a citizen of the United States, residing at New Windsor, in the county of Carroll and State of Maryland, have invented a new, original, and ornamental Design for Rabbit Hutches, of which the following is a specification, reference being had to the accompanying drawings, forming part thereof.

Fig. 1 is a front perspective view of the rabbit hutch, showing my new design.

Fig. 2 is a rear perspective view thereof.

I claim:

The ornamental design for a rabbit hutch, as shown.

ABRAHAM DEWEY STONER.
